FUEL SUPPLY SYSTEM

Milton E. Chandler, New Britain, Conn., assignor,
by mesne assignments, to Niles-Bement-Pond
Company, West Hartford, Conn., a corporation
of New Jersey

Application December 1, 1945, Serial No. 632,219

9 Claims. (Cl. 103—41)

1

This invention relates to fuel supply apparatus for internal combustion engines. It is particularly concerned with a fuel supply system wherein a pump is employed for transmitting fuel from a supply source to the engine.

An object of the invention is the provision of novel means of simple construction for controlling the supply of fuel in response to both the rate of fuel flow and the rate of airflow to the engine.

A further object is the provision of a novel and efficient relief valve for the fuel supply pump, which relief valve is controlled both by the rate of fuel flow and the rate of airflow to the engine.

A more specific feature of the invention comprises a valve element movable in response to the difference between the air differential pressure and the fuel differential pressure for controlling the by-passing of fuel from the outlet to the inlet side of the fuel pump and thereby controlling the rate of supply of fuel to the engine.

Other features of the invention will be hereinafter described and claimed.

In the accompanying drawings:

Fig. 1 is a view in longitudinal vertical section illustrating a combined pump and fuel control valve embodying features of my invention.

Fig. 2 illustrates diagrammatically a fuel supply system for an internal combustion engine embodying the fuel control mechanism of Fig. 1.

Referring to the drawings, the fuel control mechanism 10 includes (as shown in Fig. 1) a housing 12 which contains a pump 14 of generally conventional design. The pump comprises a rotor 16 having the usual blades or vanes 17, and driven by a shaft 18 which is splined at its outer end, as indicated at 19, so that it may readily be driven through a suitable connection from the engine. The inner end of shaft 18 is drivingly connected to rotor 16 by splines 21. Fuel is received by the pump through an inlet connection 20 and is discharged through an outlet 22.

A by-pass valve arrangement of known construction is provided, comprising a valve element 24 which fits into a bore 25 in the member 26, the latter being threadedly fitted into a top portion of the housing 12. Openings such as 27 provide communication between the pump inlet 20 and the portion of the bore 25 above the valve 24.

Normally, a spring 28 maintains said valve 24 in its uppermost position wherein it prevents

passage of fuel downwardly through the bore 25. If, however, the pump inlet pressure for any reason exceeds the discharge pressure by a predetermined amount, the valve 24 opens, permitting fuel to by-pass the pump rotor 16, and to flow from the inlet 20 past the valve, through chamber 29, and thence directly to the outlet 22. This arrangement is useful when two pumps are connected in series in a fluid line. If one pump fails to operate for some reason, the by-pass valve on that pump opens to allow the other pump to move fuel past it. Such by-pass arrangement is well-known, and no novelty is claimed therefor in this application.

15 The end of the pump rotor 16 opposite the shaft 18 is drivingly connected to a piston 30, which is mounted for both rotary and translatory motion in a bearing sleeve 32, fitted within an extension of the housing 12. The driving connection between the rotor 16 and piston 30 may take any suitable form for effecting rotation of said piston while at the same time permitting translation thereof. Said connection may, as shown, comprise a pinion 34 on a shaft 25 which is driven by the rotor 16 through splines 37. Pinion 34 meshes with an internal gear 36 on the piston 30, the teeth of said internal gear being of sufficient length to permit translation of the piston throughout its maximum range without disengagement of said gear 36 from said pinion 34. The piston may thus be continuously rotated with the pump rotor 16, while also being movable longitudinally in the sleeve 32.

30 35 Rotation of the pump rotor 16 draws fuel from a suitable tank or reservoir through a conduit 38 (Fig. 2) and opening 20 (Fig. 1) and impels said fuel through discharge opening 22 into a conduit 40 (Fig. 2). From said conduit the fuel may pass to a mixture control valve 42 (the portion 40' of said conduit 40 adjacent said mixture control valve being shown, for convenience, on a smaller scale than the portion of said conduit adjacent the housing 12). From the mixture control valve 42, the fuel may pass

40 45 through a jet system 44, then through a conduit 46 to a pressure control valve 48, and thence to a fuel discharge nozzle 50 in an air passage 52 which communicates with the intake manifold of the engine.

The mixture control 42 includes a disk valve 43, which, when in the position shown in the drawing (termed the "lean" position), permits fuel from the conduit 40 to flow only through conduit 54 to the jet system 44. However, said

2

disk valve is movable from the position shown to one (termed the "rich" position) in which the fuel from conduit 48 may flow to the jet system through both the conduit 54 and conduit 56, as is well understood in the art.

Fuel entering the jet system 44 through the conduit 54 passes either through a fixed restriction 58 or through a restriction 60 controlled by an enrichment valve 62 biased to closed position by a spring. Fuel flowing to said jet system through conduit 56 passes through a fixed restriction 64. Fuel flowing through the restrictions 60 and 64 also flows through a restriction 66 before entering the conduit 46.

A conduit 68 is connected at one end to said conduit 46 and at its opposite end to a passage 70 in the housing 12, which passage in turn communicates, through passage 72 in bearing sleeve 32, with a chamber 74 at the left of the piston 30. Thereby the pressure of the fuel emerging from the jet system is applied to the left hand end of said piston (as viewed in Fig. 1). At the same time, the pressure of the fuel on its way to the jet system is applied through chamber 28 to the right hand end of the piston 30. Thus said piston is subjected to the fuel pressure differential across the jet system, which pressure differential is a measure of the fuel flowing to the engine per unit of time.

The pressure control valve 48 comprises a valve member 76 secured to a diaphragm 78 which is urged by a spring 80 in a direction to close the opening 82 through which fuel must flow to reach the nozzle 50. When the pressure of the fuel in the space below the diaphragm 78 is sufficient to overcome the action of the spring 80, the valve 76 is raised, and fuel flows through said opening 82 and thence to nozzle 50. Thus the fuel flowing through conduit 46 is maintained under substantially constant pressure by the spring-actuated diaphragm 80. Pressure control valves of the type illustrated at 48 are well known, and I claim no novelty therefor in this application.

Suitably secured to the forward or lefthand end of the housing 12 is a casing 84 containing a flexible diaphragm 86, which separates said casing into a pair of chambers 88 and 90. Port 92 in chamber 88 is connected by a conduit 94 (Fig. 2) to one or more impact tubes 96 in the path of air entering the passage 52; while port 98 in chamber 90 is connected to a Venturi restriction 100 in said passage, through a conduit 102.

The diaphragm 86 is connected to piston 30 by any suitable means whereby movement of the diaphragm in either direction is imparted to said piston, without interfering with continuous rotation of the piston. One such means which may be employed to advantage is illustrated in Fig. 1, wherein a recessed member 104 passes through the center of the diaphragm and is pinned or otherwise suitably secured thereto. Rotatably mounted near one end in a bearing 106 in said member 104 is a shaft 108 which throughout the greater portion of its length extends through a bearing sleeve 110. At the aforementioned end, said shaft 108 has a head 109 which abuts against a wall of a recess in the member 104, so that movement of the diaphragm 86 to the right (Fig. 1) is transmitted to said shaft. At its other end, said shaft 108 is provided with a recessed head 112 having one or more fingers engaging openings or slots in lugs on the piston 30, one of which lugs is shown at 114, so that said shaft rotates

with said piston and also transmits longitudinal movement thereto in response to movement of the diaphragm 86. A ball 116 may, as shown, be mounted in a recess in said head 112 to provide an anti-friction thrust bearing between said shaft 108 and the piston 30.

The conduit 102 is shown communicating with a chamber 118, which chamber communicates through conduit 120 with the throat of the venturi 100. The conduit 94, which receives the total or dynamic pressure of the air at the Venturi entrance, communicates with the chamber 118 through a passage containing a restriction 122 and also controlled by a valve 124 positioned by a bellows 126 in said chamber 118. The function of said valve 124 and bellows 126 is to reduce the total pressure differential produced by the venturi 100 by an amount sufficient to correct for decrease in density of the air due to altitude or temperature, so that the pressure drop appearing across the restriction 122 is a measure of the mass of air flowing through the venturi per unit of time. This arrangement is completely described in my Patent No. 2,393,144, issued January 15, 1946. Since the pressure drop across said restriction 122 is applied to the diaphragm 86, it will be apparent that said diaphragm is subjected to a force which is a measure of the rate of said mass air flow.

In the portion of the housing 12 surrounding the bearing sleeve 32 there is provided an annular chamber 128, which chamber is in constant communication with the bore 25 and pump inlet 20 through channel 130 and openings 27. Said chamber 128 is also in constant communication with a series of ports 132, 134 leading through the sleeve 32.

The right hand end of the piston 30 covers more or less of the ports 132, 134, depending upon its lateral (as shown in the drawing) position with respect to sleeve 32, and thereby controls communication between the pump outlet 22 and the inlet 20 by way of chamber 29, ports 132 and 134, chamber 128, passage 130, and openings 27.

In the operation of the apparatus above described, the differential pressure corresponding to the mass air flow per unit of time urges the diaphragm 86 and piston 30 to the right; while the fuel pressure differential across the jet system 44, which is a measure of the rate of fuel flow to the engine, acts upon said piston to urge the latter to the left. Under normal conditions of operation, the piston will be in the position shown in Fig. 1, with communication established between outlet 22 and inlet 20 by way of chamber 128; since the pump capacity at any given engine speed is normally much greater than any fuel flow that would be required at that speed. If, now, the rate of air flow rises, the differential pressure in the chambers 88 and 90 becomes greater and shifts the piston 30 to the right, either into the position wherein back flow of fuel to the pump inlet is completely cut off, or into an intermediate position wherein said back flow is diminished. In either event, the fuel flow to the engine is increased, and the fuel differential pressure acting upon piston 30 is also increased. This increased fuel differential pressure urges the piston to the left, so that said piston comes to rest in a position wherein the force exerted on the piston by said fuel pressure differential balances that of the increased air pressure differential. If, now, the air flow decreases, the fuel-pressure differential moves the piston 30 further to the left, increasing the back flow of

fuel to the pump inlet and decreasing the fuel flow to the engine, until the piston reaches a position wherein the consequent decreased fuel pressure differential balances the diminished air pressure differential.

It will thus be apparent that, through the apparatus above described, there is maintained a substantially constant ratio between the fuel flow and the air flow. This ratio may, of course, be varied by operation of the mixture control valve 42.

It will also be apparent that, through the above described apparatus, an increase of pump discharge pressure when the piston 39 is in balanced position will move said piston to the left from said position, allowing further flow of fuel back to the pump inlet and relieving said discharge pressure. Said piston continues to open wider the path of return fuel flow through openings 134 and 132, until the pump discharge pressure is reduced to such a value that the fuel pressure differential is balanced by the air pressure differential. Thus, for a given air differential pressure the pump discharge pressure is maintained substantially constant, and this is achieved through the same elements that maintain a substantially constant ratio between the fuel and air flows, and without the necessity of a separate pump discharge pressure relief valve as has heretofore been employed.

If desired, a spring 140 may be provided for urging the diaphragm 86 to the right in Fig. 1 to insure that back flow of fuel through the relief passage 132 is restricted to any preferred extent when no air is flowing through the venturi 109 or when the air differential pressure is very small, as for low rates of air flow corresponding to idling positions of the throttle.

The pressure of spring 140 on the diaphragm 86 may be adjusted as desired by conventional spring-adjusting means, such as a nut 142 and screw 144.

Throughout the operation of the engine the piston 39 is rotated continuously, so that static friction is eliminated between said piston and the bearing sleeve 32. The piston is thus enabled to respond with particular accuracy and precision to slight changes in the air and fuel pressure differentials.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

I claim:

1. A fuel control system for internal combustion engines, comprising a fuel pump having a fuel inlet and a fuel discharge outlet, means for conducting fuel from said outlet, said conducting means including a jet system, means comprising a relief valve member for controlling a back flow of fuel from said discharge outlet to said fuel inlet, and means for subjecting opposite portions of said member to the fuel differential pressure across said jet system.

2. A fuel control system for internal combustion engines, comprising a fuel pump having a fuel inlet and a fuel discharge outlet, means for conducting fuel from said outlet, a relief valve member subject on one face to the fuel discharge outlet pressure, a restriction in said conducting means, means for subjecting an opposite face of said valve member to the fuel pressure in said

conduit means downstream of said restriction, and means controlled by said valve member for the passage of fuel from said discharge outlet back to said fuel inlet.

3. A fuel control system for internal combustion engines, comprising a fuel pump having a fuel inlet and a fuel discharge outlet, means for conducting fuel from said outlet, a restriction in said conducting means, a valve member subject on one face to the fuel discharge pressure of said pump, means controlled by said member in response to an increase in pump discharge pressure for relieving the latter by flow of fuel back to the pump inlet, means for subjecting the opposite face of said valve member to fuel pressure in said conducting means downstream of said restriction, and means for applying to said member a variable controlling force opposing the fuel pressure differential acting thereon.

4. A fuel control system for internal combustion engines, comprising a fuel pump having a fuel inlet and a fuel discharge outlet, means for conducting fuel from said outlet, said conducting means having a restriction therein, a control casing having a port therein, a piston movable in said casing and cooperating with said port for controlling a back flow of fuel from said discharge outlet to said fuel inlet, said piston being subjected on one face to the fuel pressure at said pump discharge outlet, means for subjecting the opposite face of said piston to the fuel pressure at a point in said conducting means downstream of said restriction whereby opposite faces of said piston are subjected to the differential pressure of fuel flowing through said conducting means, and means for applying to said piston a variable controlling force acting in a direction opposite to that of said fuel differential pressure.

5. A fuel control system for internal combustion engines, comprising a fuel pump having a fuel inlet and a fuel discharge outlet, means for conducting fuel from said outlet, said conducting means having a restriction therein, a control casing having a port therein, a piston movable in said casing and cooperating with said port for controlling a back flow of fuel from said discharge outlet to said fuel inlet, said piston being subjected on one face to the fuel pressure at said pump discharge outlet, means for subjecting the opposite face of said piston to the fuel pressure at a point in said conducting means downstream of said restriction whereby opposite faces of said piston are subjected to the differential pressure of fuel flowing through said conducting means, means for applying to said piston a variable controlling force acting in a direction opposite to that of said fuel differential pressure, and means for continuously rotating said piston while said pump is in operation.

6. A fuel control system for internal combustion engines, comprising a rotary fuel pump, a fuel inlet and a fuel outlet for said pump, a fuel discharge conduit for receiving fuel from said outlet, a metering restriction in said discharge conduit, a pressure relief conduit connecting said outlet to said inlet, a cylinder having at least one port extending through a wall thereof, said cylinder and port forming a portion of said pressure relief conduit, a piston rotatably and slidably mounted in said cylinder adjacent said port so as to vary the opening of said port upon sliding movement, said pressure relief conduit including a portion subjecting the end of said piston adjacent said port to the pump discharge pressure, means for subjecting the op-

posite end of said piston to the pressure in said discharge conduit downstream from said restriction, and means drivingly connecting said pump and piston to cause continuous rotation of said piston during operation of said pump and thereby to prevent sticking of said piston during sliding movement thereof.

7. A fuel control system for internal combustion engines, comprising a rotary fuel pump, a fuel inlet and a fuel outlet for said pump, a pressure relief conduit connecting said outlet to said inlet, a cylinder having at least one port extending through a wall thereof, said cylinder and port forming a portion of said pressure relief conduit, a piston rotatably and slidably mounted in said cylinder adjacent said port so as to vary the opening of said port upon sliding movement, said pressure relief conduit including a portion subjecting the end of said piston adjacent said port to the pump discharge pressure, and means drivingly connecting said pump and piston to cause continuous rotation of said piston during operation of said pump and thereby to prevent sticking of said piston during sliding movement thereof.

8. A fluid flow control system, comprising a rotary pump, an inlet and an outlet for said pump, a discharge conduit for receiving fluid from said outlet, a metering restriction in said discharge conduit, a pressure relief conduit connecting said outlet to said inlet, a cylinder having at least one port extending through a wall thereof, said cylinder and port forming a portion of said pressure relief conduit, a piston rotatably and slidably mounted in said cylinder adjacent said port so as to vary the opening of said port upon sliding movement, said pressure relief conduit including a portion subjecting the end of said piston adjacent said port to the pump discharge pressure, means for subjecting the opposite end of said piston to the pressure in said discharge conduit downstream from said restriction,

and means drivingly connecting said pump and piston to cause continuous rotation of said piston during operation of said pump and thereby to prevent sticking of said piston during sliding movement thereof.

9. A fluid flow control system, comprising a rotary pump, an inlet and an outlet for said pump, a pressure relief conduit connecting said outlet to said inlet, a cylinder having at least one port extending through a wall thereof, said cylinder and port forming a portion of said pressure relief conduit, a piston rotatably and slidably mounted in said cylinder adjacent said port so as to vary the opening of said port upon sliding movement, said pressure relief conduit including a portion subjecting the end of said piston adjacent said port to the pump discharge pressure so that said discharge pressure acts on said piston in a direction to increase said port openings, means for applying a controlling force to said piston in opposition to said discharge pressure, and means drivingly connecting said pump and piston to cause continuous rotation of said piston during operation of said pump and thereby to prevent sticking of said piston during sliding movement thereof.
